US00D946072S

(12) **United States Design Patent** (10) **Patent No.:** **US D946,072 S**
(45) **Date of Patent:** **** Mar. 15, 2022**

(54) **CAMERA HOUSING**

(71) Applicant: **GoPro, Inc.**, San Mateo, CA (US)

(72) Inventors: **John George Muhlenkamp, IV**,
Brisbane, CA (US); **Bessy Liang**, San
Jose, CA (US); **Huy Phuong Nguyen**,
San Mateo, CA (US); **Daniel J. Coster**,
San Francisco, CA (US)

(73) Assignee: **GoPro, Inc.**, San Mateo, CA (US)

(**) Term: **15 Years**

(21) Appl. No.: **29/745,857**

(22) Filed: **Aug. 10, 2020**

(51) **LOC (13) Cl.** **16-01**

(52) **U.S. Cl.**

USPC **D16/200**

(58) **Field of Classification Search**

(57) **CLAIM**

The ornamental design for a camera housing, as shown and described.

DESCRIPTION

FIG. 1 is a top, front and right side perspective view of a camera housing showing our new design;

FIG. 2 is a bottom, rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top, front and right side perspective view thereof, shown in condition of use with a camera disclosed in broken lines to illustrate an environment;

FIG. 10 is a bottom, rear and left side perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken lines showing a camera in FIGS. 9-16 represent environmental structure and form no part of the claimed design.

1 Claim, 10 Drawing Sheets
